UNITED STATES PATENT OFFICE.

GLENN E. EDMUNDS, OF COLUMBUS, OHIO, ASSIGNOR TO THE BONNEY-FLOYD COMPANY, OF COLUMBUS, OHIO, A CORPORATION OF OHIO.

MINE CAR.

Application filed December 28, 1926. Serial No. 157,550.

This invention relates to cars, and more particularly to cars of the type used in coal mines and industrial plants.

The invention has to do with cars of the type disclosed in the patent to Edmunds, 1,525,072, granted Feb. 3, 1925.

The principal object of the invention is to provide a car provided with a body frame of rugged and durable construction, the parts of which may be manufactured and assembled at reasonable cost, and when assembled provide a car of greater load capacity than the average car of substantially the same overall dimensions and weight.

15 The invention has to do particularly with the construction of the body and its base frame, which rests upon a truck unit of the type disclosed in the above-mentioned patent.

20 Other novel features of the invention relate to the bumper construction and the wheel mounting.

As will be understood by one skilled in the art, cars of this character are used in mines where the rooms and entries are low and narrow; consequently, it is necessary that the dimensions of the car be kept within certain recognized limits, and that any increase in the capacity must be obtained 25 by a lowering of the center of gravity and an enlargement of the carrying space within these limits. Furthermore, since cars of this type are subjected to rough usage, and severe strains, it is necessary that all the 30 parts be securely united so as to form a substantially integral structure.

In the accompanying drawings, there is shown a preferred embodiment of the invention, in which:

40 Figure 1 is a side elevational view.

Figure 2 is a bottom plan.

Figure 3 is a longitudinal section on the line 3—3 of Figure 2.

Figure 4 is a transverse section on the line 45 4—4 of Figure 2, looking in the direction of the arrows.

Figure 5 is a transverse section on the line 5—5 of Figure 2.

Figure 6 is a perspective of the body base 50 frame mounted upon the truck.

Figure 7 is a fragmentary sectional view showing the wheel mounting.

Referring to the drawings for a more detailed description, T indicates the truck

which comprises a pair of sill castings at 55 each side, each pair of castings having the wheels therebetween mounted on stub axles supported by the castings. In the drawings 10, 11, indicate the inner castings, and 12, 13 the outer castings of each pair. The two pairs of castings are united by suitable cross girts such as the end cross girts 14, 15 extending between the inner castings 10, 11 and secured to inwardly extending lugs 16, 60 thereon. A central cross girt 17 extends through the inner castings 10, 11 to which it is connected at 17', to the outer castings, and is secured at 18 to inwardly extending lugs 19 on the outer castings. This truck 65 unit is supported by means of the wheels 20, which are mounted upon stub axles 21, having suitable bearings 22 in the castings. The axles are free to rotate or creep in their bearings 22 and although they will not 70 rotate with the wheels the axles will intermittently or slowly rotate, thus maintaining the lubricant therein in a fluid state and continuously fed to the wheel bearings. Each axle is hollow, being provided with a 75 lubricant entry port 24, and is held in position as by means of a cotter pin 25 extending through a protecting hood 26 extending outwardly from the axle bearings in the outer casting.

When it is necessary to drop one of the 80 wheels, the cotter pin may be withdrawn and the axle pulled outwardly through the wheel by means of a suitable axle puller, the end of which may be threaded into the 85 threaded socket 27.

The truck above described, which, in construction, is similar to that illustrated in the patent mentioned, with the exception of the wheel mounting, is adapted to receive the body B which has a base frame, illustrated 90 most clearly in Figure 6. The body base frame comprises pairs of angle bars arranged at opposite sides, the members of each pair of angle bars being suitably connected together; and the two pairs may also 95 be connected by means of end cross members.

Referring to the Figures 4, 5 and 6, the inner angle bar 29 of each pair instead of being of integrally fabricated formation, consists of a longitudinally extending center 100 or web plate 30 having inwardly extending horizontal flanges 31. These flanges are formed by providing angle members which

have vertical flanges 31' adapted to receive securing means, such as rivets 32, for securing the same to the web 30.

It will be observed that the inwardly extending flanges 31 of the inner angle bars are not continuous, since they are arranged in substantially the same horizontal plane with the truck cross girts 14, 15, 17 to assist the latter in supporting the car floor. Between the cross girts, instead of providing flanges 31 on the body base frame, the sill bars or castings of the truck are formed integrally with inwardly extending webs or platforms 33 arranged in substantially the same horizontal plane of the cross girts and flanges 31 of the body base frame; thus the floor is provided substantially throughout its length between the base frame bars 29 with practically a continuous support. The inner bars of the base frame cooperate with outer bars 34 in the form of angle irons, which have inwardly disposed horizontal flanges 35 resting upon the top surfaces of the outer truck castings 12, 13. The flanges 35 serve to support the base frame on the truck and may be assisted by securing the central web 30 of the inner bars 29 to the inner truck castings, as by rivets or bolts 37. As will be observed, the inner base frame sill bars also have outwardly extending horizontal flanges 30', which may be either continuous so as to rest upon the inner truck castings, or, as illustrated in the drawings, cut away over the top surface of the inner truck castings for a purpose later to be described.

The outwardly extending horizontal flanges 30' are in substantially the same plane with the top surface of the inner truck castings 10, 11, and are formed by securing the vertical flanges 38 (Fig. 1) of suitable angle irons to the web 30. It will be understood that instead of forming the inner base frame bars 29 of separate elements, as illustrated in the drawings, these bars may be of one-piece construction, which at their ends, are of substantially Z-shaped cross-sectional formation, due to the provision of the inwardly extending floor supporting flanges 31 and the outwardly extending flanges 30' thereabove.

At their ends, the members of each pair of base frame bars are connected by short angle members 39 (Fig. 6) riveted to the horizontal flanges 35 of the outer bars. The two pairs may be joined at their ends by suitable cross members. In the present instance, at one end of the base frame, a cross strip 40 extends between the outer angles 34 and is riveted to the depending vertical flanges 39' of the angle members 39. It is also joined by means of angle brackets 41 to the webs 30 of the inner base frame bars 29.

At the opposite end of the base frame, the pairs of bars may be joined by a plate 42 secured to the depending flanges 39' of the

angle brackets 39 at its lower end, and extended upwardly to form the end wall of the car (Fig. 4). Angle brackets 41', similar in construction to the angles 41 securing the cross member 40 in position, serve to unite the end bracing wall 42 to the base frame. It will be understood that the end wall 42, constituting as it does a bracing element for the body base frame, as well as a portion of the body wall, effects a very secure union between the base frame and the super-posed body structure. It is joined along its side edges by means of interior angle brackets 43, with the side walls 44, which, at their lower edges, fit within the vertical flanges 34' of the outer base frame angles 34. The opposite end of the car is closed by a vertically swinging gate 46, the lower edge of which is positioned above the end cross member 40 of the base frame.

The bottom of the body may be formed by a central floor plate 47, carried by the inwardly extending flanges 31 of the base frame by the cross girts of the truck and by the inwardly extending platforms 33 on the truck sill castings. It will be understood, of course, that although the floor is positioned above these elements, it may be carried below the same. The spaces between the members of each pair of base frame angle bars may be closed by wheel hoods 48 having base flanges 49 which rest directly upon the inner truck sill castings 10, 11 (Fig. 5), and upon the inwardly extending horizontal flanges 35 of the outer base frame angle bars. It is for the purpose of maintaining the wheel hoods in substantially horizontal position and to bring the top surface of the higher truck sill castings 10, 11 in alignment with the supporting flanges of the outer base frame angle bars (Fig. 4) that the outwardly extending flanges 30' on the inner angle bars are cut away for a substantial distance. By reference to Figure 5, it will be observed that the top surface of the inner and outer sill castings are not in horizontal alignment, due to the greater height of the inner sill castings, but this is compensated for by cutting away the outwardly extending flanges 30' of the base frame to permit the wheel hoods to rest directly upon the inner truck sill castings. The spaces between the pairs of base frame angles at opposite sides of the hoods, may be filled by suitable floor plates 50, resting upon and secured to the horizontal flanges 35, 30', of the base frame side or angle bars.

At each end, the car may be provided with a bumper which is in the form of a hollow steel casting, having a curved outer depending flange 51 and a straight back vertically depending flange 52. The two flanges are connected by a top horizontal web 53 and vertical reinforcing webs or ribs 54 spanning

the space between the flanges 51 and 52. The top surface of each bumper is socketed to receive the base 55 of a coupling tongue 56 and bolts 57 pass through the base of the tongue into the top web 53 of the bumper. The tongue and bumper being separately cast, may be readily separated should it be necessary to replace the coupling tongue because of breakage. This construction renders it unnecessary to discard the entire bumper should the coupling tongue break, and is a substantial improvement upon constructions heretofore employed in which the tongue is cast integrally with the bumper. Moreover, it has substantially the strength of an integral construction, due to the seating of the base 55 of the tongue in the socket on the top surface of the bumper; the strain of the pull does not tend to rock the tongue about its anchorage to the same extent as if the latter were simply secured to an unsocketed top surface of the bumper.

As will be understood, the construction as illustrated and described may be varied considerably without departing from the invention which is defined in the following claims.

I claim:

1. In a mine car, a truck unit comprising a pair of sill bars at each side, cross girts connecting said pairs of sill bars and floor supporting members formed integrally with the inner of said sill bars and extending inwardly therefrom.

2. In a mine car, a truck unit comprising a pair of sill bar castings at each side, cross girts connecting said pairs of sill bars, and floor supporting platform members formed integrally with the inner of said sill bars and extending inwardly therefrom.

3. In a mine car, a truck unit comprising a pair of sill bars at each side, cross girts connecting said pairs of sill bars below their top surfaces and floor supporting platform members formed integrally from said sill bars in substantially the same horizontal plane with said cross girts.

4. In a mine car, a truck unit comprising a pair of sill bars at each side, cross girts connecting said pairs of sill bars below their top surfaces and floor supporting platform members formed integrally from said sill bars in substantially the same horizontal plane with said cross girts and between said cross girts.

5. In a mine car, a truck unit comprising a pair of sill bars at each side, cross girts connecting said pairs of sill bars below their top surfaces and floor supporting platform members formed integrally from said sill bars in substantially the same horizontal plane with said cross girts and between said cross girts, a body base frame on said truck unit comprising angle members carried by the inner sill bars and having horizontal flanges projecting inwardly from the sill

bars substantially in the horizontal plane of said cross girts whereby to assist in supporting the car floor.

6. In a mine car, a truck unit comprising a pair of sill bars at each side, cross girts connecting said pairs of sill bars below their top surfaces and floor supporting step members formed integrally from said sill bars in substantially the same horizontal plane with said cross girts and between said cross girts, and a body base frame on said truck unit comprising angle members substantially Z-shaped in cross section carried by the inner sill bars and having horizontal flanges projecting inwardly from the sill bars substantially in the horizontal plane of said cross girts whereby to assist in supporting the car floor, and horizontal flanges extending outwardly.

7. In a mine car, a truck unit comprising a pair of longitudinal sill bars at each side, wheels between each pair of sill bars, cross girts connecting said sill bars and a body base frame comprising an angle bar connected with each inner sill bar and extending longitudinally thereof, each angle bar having a horizontal flange extending inwardly and being adapted to assist in supporting the car floor.

8. In a mine car, a truck unit comprising a pair of longitudinal sill bars at each side, wheels between each pair of sill bars, cross girts connecting said sill bars and a body base frame comprising an angle bar connected with each inner sill bar and extending longitudinally thereof, each angle bar having a horizontal flange extending inwardly below the top surface of the sill bar and being adapted to assist in supporting the car floor.

9. In a mine car, a truck unit comprising a pair of longitudinal sill bars at each side, wheels between each pair of sill bars, cross girts connecting said sill bars and a body base frame comprising an angle bar connected with each inner sill bar and extending longitudinally thereof, each angle bar being substantially Z-shaped in cross section and having a horizontal flange extending inwardly and being adapted to assist in supporting the car floor, and another horizontal flange extending outwardly in substantially the horizontal plane of the top of the inner sill bar.

10. In a mine car, a truck unit comprising a pair of longitudinal sill bars at each side, wheels between each pair of sill bars, cross girts connecting said sill bars and a body base frame comprising an angle bar connected with each inner sill bar and extending longitudinally thereof, each angle bar being angular in cross section and having a horizontal flange extending inwardly below the top surface of the sill bar and being adapted to assist in supporting the car floor,

- and another angle bar at each side forming an integral part of the base frame and having a horizontal flange resting on the outer sill bar.
- 5 11. In a mine car, a truck unit comprising a pair of longitudinal sill bars at each side, wheels between each pair of sill bars, cross girts connecting said sill bars and adapted to support a car floor therebetween, and a 70 body base frame comprising an angle bar connected with each inner sill bar and extending longitudinally thereof, each angle bar having a horizontal flange extending inwardly below the top surface of the sill 75 bar and being adapted to assist in supporting the car floor, said flanges and cross girts being in substantially the same horizontal plane below the top surfaces of the sill bars.
- 10 12. In a mine car, a body having a base frame structure comprising a pair of spaced side bars at each side, and cross members connecting said pairs of side bars, each of 80 said inner side bars being angular in cross section and having an inwardly projecting horizontal flange adapted to support a car 85 floor.
- 15 13. In a mine car, a body having a base frame structure comprising a pair of spaced side bars at each side, and cross members connecting said pairs of side bars, each of 90 said inner side bars being angular in cross section and having an inwardly projecting horizontal flange adapted to support a car 95 floor, and an outwardly projecting horizontal flange.
- 20 14. In a mine car, a body having a base frame structure comprising a pair of spaced side bars at each side, and cross members connecting said pairs of side bars, each of 100 said inner side bars being angular in cross section and having an inwardly projecting horizontal flange adapted to support a car floor, and an outwardly projecting horizontal flange spaced vertically above the 105 horizontal flange.
- 25 15. In a mine car, a body having a base frame structure comprising a pair of spaced side bars at each side, and cross members connecting said pairs of side bars, each of 110 said inner side bars being angular in cross section and having an inwardly projecting horizontal flange adapted to support a car floor, and the outer side bars having horizontal flanges adapted to rest upon sill bars 115 of a supporting truck.
- 30 16. In a mine car, a body base frame structure comprising a pair of spaced side bars at each side, and cross members connecting the pairs of side bars, the inner 120 side bars being angular in cross section, and each having an outwardly extending horizontal flange cut away a substantial distance intermediate its ends, and an inwardly extending horizontal flange spaced vertically from said first mentioned horizontal flange, and adapted to support a car floor, said angle members being substantially Z-shaped in cross section.
- 35 17. In a mine car, a body base frame structure comprising a pair of spaced side bars at each side, cross members connecting the pairs of side bars, the inner side bars being angular in cross section, and each having an outwardly extending horizontal flange cut away a substantial distance intermediate its ends, and an inwardly extending horizontal flange spaced vertically from said first mentioned horizontal flange, and adapted to support a car floor, said angle members being substantially Z-shaped in cross section.
- 40 18. In a mine car, a body base frame structure comprising a pair of spaced side bars at each side, and cross members connecting the pairs of side bars, the inner side bars being angular in cross section, and each having an outwardly extending horizontal flange cut away a substantial distance intermediate its ends, and an inwardly extending horizontal flange spaced vertically from said first mentioned horizontal flange, and adapted to support a car floor, said angle members being substantially Z-shaped in cross section.
- 45 19. In a mine car, a body base frame structure comprising a pair of spaced side bars at each side, and cross members connecting the pairs of side bars, the inner side bars being angular in cross section, and each having an outwardly extending horizontal flange cut away a substantial distance intermediate its ends, and said outer side bars being angular in cross section, and each having a horizontal flange adapted to rest upon the sill bar of a supporting truck.
- 50 20. In a mine car, a body base frame structure comprising a pair of spaced side bars at each side, and cross members connecting the pairs of side bars, the inner side bars being angular in cross section, and each having an outwardly extending horizontal flange cut away a substantial distance intermediate its ends, and an inwardly extending horizontal flange spaced vertically from said first mentioned horizontal flange, and adapted to support a car floor, said angle members being substantially Z-shaped in cross section, and said outer side bars being angular in cross section.
- 55 21. In a mine car, a body base frame structure comprising a pair of spaced side bars at each side, and cross members connecting the pairs of side bars, the inner side bars being angular in cross section, and each having an outwardly extending horizontal flange cut away a substantial distance intermediate its ends, and an inwardly extending horizontal flange spaced vertically from said first mentioned horizontal flange, and adapted to support a car floor, said angle members being substantially Z-shaped in cross section, and said outer side bars being angular in cross section.
- 60 22. In a mine car, a body having a base frame structure comprising a pair of spaced side bars at each side, cross members connecting the pairs of side bars, the inner side bars being angular in cross section, and each having an outwardly extending horizontal flange cut away a substantial distance intermediate its ends, and an inwardly extending horizontal flange spaced vertically from said first mentioned horizontal flange, and adapted to support a car floor, said angle members being substantially Z-shaped in cross section, and said outer side bars being angular in cross section, each having a vertical flange extending upwardly from a horizontal flange.
- 65 23. In a mine car, a body having a base frame structure comprising a pair of spaced side bars at each side, cross members connecting the pairs of side bars, the inner side bars being angular in cross section, and each having an outwardly extending horizontal flange cut away a substantial distance intermediate its ends, and an inwardly extending horizontal flange spaced vertically from said first mentioned horizontal flange, and adapted to support a car floor, said angle members being substantially Z-shaped in cross section.

necting said pairs of side bars, said side bars being in substantially the same horizontal plane and being angular in cross section, and the inner one of each pair having a horizontal flange extending inwardly from a vertical flange and adapted to support a car floor.

23. In a mine car, a body having a base frame structure comprising a pair of spaced side bars at each side, cross members connecting said pairs of side bars, said side bars being in substantially the same horizontal plane and being angular in cross section, and the inner one of each pair having a horizontal flange extending outwardly from a vertical flange and adapted to support a car floor.

In testimony whereof I have hereunto set my hand.

GLENN E. EDMUNDS.
